(57) CLAIM

The ornamental design for an element of a shoe upper, as shown and described.

DESCRIPTION

FIG. 1 is a side view of an element of a shoe upper showing a new design; and

FIG. 2 is a perspective view thereof;

FIG. 3 is a right side view of an element of a shoe upper; and,

FIG. 4 is a right side perspective view thereof.

The even broken line is environmental only and forms no part of the claimed design.
